UNITED STATES PATENT OFFICE.

FRANK E. HULETT, OF CLEVELAND, AND LEIF LEE, OF YOUNGSTOWN, OHIO.

MINE HOIST.

Application filed October 15, 1920. Serial No. 417,115.

To all whom it may concern:

Be it known that we, FRANK E. HULETT and LEIF LEE, citizens of the United States, residing at Cleveland, Cuyahoga County, 5 Ohio, and Youngstown, Mahoning County, Ohio, respectively, have invented certain new and useful Improvements in Mine Hoists, of which the following is a specification.

10 This invention relates to improvements in hoisting and conveying apparatus, and more particularly to hoisting mechanism for elevating coal and other deposits from mines.

15 Heretofore it has been customary in mine hoists to employ a skip or bucket of small capacity, for example twelve to fifteen tons, and to run the apparatus at high speed so as to produce tonnage by rapid filling, elevating, discharging and lowering operations. This is undesirable by reason of the 20 rapid loading and dumping as well as the high speed of the apparatus, and such operation results in much loss of time due to frequent periods of stopping and starting 25 the apparatus. The expense of operation according to the old method is also excessive due to power consumption, cost of maintenance, etc.

30 The present invention is intended to overcome the difficulties and disadvantages arising out of the former practice by the employment of a skip or bucket of large capacity, as for instance fifty tons, whereby 35 the apparatus may be operated at a most desirable speed and yet a great tonnage will result. It is in the attaining of this end that the present improvements have been devised, such improvements being the arrangement 40 of the counter-weights whereby a portion of the counter-weight controls the door; the entire counter-weight assists in elevating the load; the load upon the hoisting mechanism during raising and lowering 45 operations is equalized by the suitable arrangement of counterweights; and whereby other advantageous results are obtained due to features of construction and arrangement as will appear.

50 The invention may be briefly summarized as consisting in the construction and combination of parts set forth in the following description, drawings and claims.

55 Referring first to the drawings, Fig. 1 is a view in elevation showing the apparatus;

Fig. 2 is a side elevation of the counter-weights; Fig. 3 is a detail view of the counterweights showing the manner of connecting portions together; Fig. 4 is a sectional view through the mine shaft; Fig. 5 is an 60 end view of the skip or bucket; Fig. 6 is a front view of the skip or bucket with the door closed; Fig. 7 is a view similar to Fig. 5 showing the arrangement of the cables and rope; Fig. 8 is a plan view taken above 65 the frame work or superstructure showing the arrangement of cables; Fig. 9 is a side elevation of the arrangement shown in Fig. 7; Fig. 10 is a side elevation of the hoisting apparatus; Fig. 11 is a top plan view 70 of the hoisting apparatus; and Fig. 12 is a diagrammatic view of my invention.

In the arrangement shown, the mine shaft 1 is provided with a suitable hopper 2 discharging into a chute 3. The discharge of 75 this chute is controlled by a door 4. The chute 3 is adapted to convey the coal or other deposit to the mine shaft 1. Above the mine shaft is a superstructure comprising a frame 5, supporting suitable guide rails 6 80 and lump bins 7 and 8. This superstructure also supports a suitable head frame 9. Extending upward from the bottom of the shaft and also upward through the superstructure are suitable opposed rails 10 and 85 11 for the door counterweight, as will appear, and another pair of rails 12 and 13 for the main counterweight. These rails are supported on brackets 14 secured to suitable beams 14^a arranged in the shaft and in the 90 superstructure. Slidably mounted on the rails 6 is a skip or bucket which comprises a rectangular shaped casing 15 having an inclined bottom 16 extending from one side toward the lower edge of the opposite side. 95 Wheels 6^a on the skip engage the rails 6. Adjacent to the lower edge of one side is a suitable dump opening adapted to be closed by a door 17 hinged at 18 and extending from one side of the skip or bucket 100 to the other. This door when open serves as a chute. Attached to each end of this door are suitable chains 19 which pass between guide rollers 20 and 21 and up into guide channels 22, one being attached to each end 105 of the door. Secured to the ends of the chain are suitable clips 23 which are attached to turn-buckles 24, in turn connected to cable ends 25 on the ends of door cables 26. The right hand door cable 26, as shown 110

in Fig. 8, passes over a sheave 27 suitably supported in the head frame 9 and thence over a double groove sheave 28. The other door cable 26 passes over a roller 29 and thence in the other groove of the double groove sheave 28. Both of these cables 26 pass down and are connected to suitable bolts 30 adjustably mounted in the cross member 31 which is secured to suitable door weight bolts 32 passing down through the main door weight portions 33. These main door weight portions have notches 34 in their ends adapted for engagement with the rails 10 and 11. Secured to the main door weight portions 33 by means of bolts 33^a are the auxiliary portions 35 which are likewise provided with recesses similar to those indicated at 34, and these recesses likewise receive the rails 10 and 11. The arrangement of the weight in two sections, as described, provides ready means for applying the weights to the rails. This weight is sufficient to hold the door closed against the weight of the coal in the skip as it presses against the same. It will be seen from the foregoing that the door weights will be suspended from the door and will tend to hold the door closed, but if the door weights were arrested in their downward movement, then the door would tend to open; and to produce this action a suitable yielding platform or bumper 36 is provided at the bottom of the shaft 1.

Secured to each end of the skip or bucket 35 is a pair of counterweight cables 37 and 38 which pass over double groove sheaves 39 and 40 respectively, and thence around the suitable drums 41 and 42 respectively, to which the ends of these cables are secured for winding. These drums 41 and 42 are supported in a suitable frame 43 located in a power house 44. These drums 41 and 42 are driven by pinions 45 and 46 respectively, and these pinions are supported and driven by a shaft 46', carrying a gear 47 driven by a pinion 48 operated by a suitable motor 49. The shaft 50 of this motor is provided with suitable braking mechanism consisting of the shoes 51 and 52 pivoted at 53 and 54 respectively, and suitably connected to a weighted lever 55. This lever 55 is actuated by a rod 56, connected to a lever 57, one end of which lever is connected to a solenoid core 58, co-operating with a solenoid coil 59. This solenoid is actuated in series with motor by proper electric connections. Shaft 46' is also driven by a second gear 60 which meshes with a pinion 61 driven by a motor 62. The shaft of this motor is also provided with a brake similar to that already described. Shaft 46' is further provided with a pinion 63, meshing with a gear 64, secured to a main counter-weight drum 65 to which are attached the ends of a pair of cables 66 for winding thereon. These

cables pass over a double groove sheave 67, supported in a head frame and thence pass down and are secured to a main counter-weight cross member 68, connected to main counter-weight bolts 69 which pass through the main counter-weight portions 70. These main counter-weight portions are similar to but larger than the door counter-weight portions 33. Secured to these main counter-weight portions 70 are auxiliary portions 71. This main counter-weight engages the rails 12 and 13. The portions 70 and 71 constitute a sectional counterweight. The arrangement of cables on the drums 41, 42 and 65 is such that when the skip or bucket ropes are being wound the main counterweight cables are being unwound, and vice versa. The skip and door counterweights together constitute a divided counterweight.

From the foregoing it will be seen that when the skip or bucket descends in empty condition its door will be closed as soon as the door counterweight is "cut in" so as to be effective and the motors driving the drums will elevate the main counter-weight, the weight of the skip or bucket being sufficient to elevate the door counter-weight. When the skip reaches the bottom of the shaft it is loaded and then elevated until the door counter-weights are arrested by the yielding platform, when the skip or bucket will move upward permitting the door to open and discharge its load into the lump bin. During the elevating operation the motors driving the drums are raising a load corresponding to the load upon the motors when lowering the skip or bucket, in that the excess of the load over the counter-weights is substantially equal to the excess of the counter-weights over the empty skip. It is true that part of the counterweight is relieved or "cut out" when the skip or bucket reaches its uppermost position, but that has the advantage of merely slowing up the skip or bucket at the upper end of its travel, which makes it possible to work under closer head room clearances. The lowering speed of the empty skip is greater at the start, that is until the door is closed; which assists in overcoming the inertia of the counterweights. By having the door of the skip serve as a chute, it is not necessary to overturn the skip in dumping the same and consequently less head room is required. The use of a large and wide skip makes possible a simplifying of the loading tipple at the bottom as well as the lump bin at the top. The form of skip also facilitates the loading of the same. Furthermore, my invention effects a reduction in power consumption, reduces the speed of hoisting and lowering, allows more time for loading and unloading, and reduces the cost of up-keep. The danger of accident is also lessened by using my invention.

Other advantages will be apparent to those who are familiar with the art to which it relates.

What we claim is:

5. 1. In a mine hoist having a discharge means, a skip, a divided counterweight therefor, part of the counterweight being operatively connected to said discharge means, means for raising the skip and lowering the counterweight, and vice versa, and means for automatically controlling said counterweight and thereby control the discharge of said skip.
10. 2. In a mine hoist having a discharge means, a skip, a divided counterweight therefor, part of said counterweight being operatively connected to said discharge means, means for raising the skip and lowering the counterweight, and vice versa, and means for automatically controlling said counterweight and thereby discharge said skip at a predetermined point in its travel.
15. 3. In a mine hoist, a skip having a door, a divided counterweight therefor, part of the counterweight being operatively connected to the door of the skip, means for raising the skip and lowering the counterweight, and vice versa, and means for automatically controlling said counterweight and thereby control the operation of the door of the skip.
20. 4. In a mine hoist, a skip having a door adapted when open to serve as a chute, a divided counterweight therefor, part of the counterweight being operatively connected with said door, means for raising the skip and lowering the counterweight, and vice versa, and means for automatically controlling said counterweight and thereby control the operation of the door of the skip at a predetermined point in its travel.
25. 5. In a mine hoist, a skip having a door, a divided counterweight therefor, part of the counterweight being operatively connected to the door of the skip, means for raising the skip and lowering the counterweight, and vice versa, and means for automatically controlling said counterweight and thereby discharge said skip at a predetermined point in its travel.
30. 6. In a mine hoist, a skip, a door for said skip, a counterweight for the skip, a counterweight for the door, means for raising the skip and lowering the counterweights, and vice versa, and means for automatically relieving the door of its counterweight at a predetermined point in the upward travel of the skip to open the door.
35. 7. In a mine hoist, a skip, a door for said skip, a counterweight for the skip, a counterweight for the door, means for raising the skip and lowering the counterweights, and vice versa, said door being held closed by the door counterweight against the weight of the contents of the skip, and means for automatically relieving the door of its counterweight at a predetermined point in the upward travel of the skip to open the door.
40. 8. In a mine hoist, a skip, a door for said skip, a counterweight for the skip, a counterweight for the door, means for raising the skip and lowering the counterweight, and vice versa, and means for automatically relieving the door of its counterweight at a predetermined point in the upward travel of the skip to open the door, the weight of the empty skip being greater than that of the door counterweight.
45. 9. In a mine hoist, a skip, a door for said skip, a counterweight for the skip, a counterweight for the door, means for raising the skip and lowering the counterweights, and vice versa, the parts being so constructed and arranged that the power required for raising the loaded skip and lowering the empty skip is approximately the same.
50. 10. In a mine hoist, a skip, a door for said skip, a counterweight for the skip, a counterweight for the door, means for raising the skip and lowering the skip counterweight, and vice versa, and a separate operative connection between the door and its counterweight.
55. 11. In a mine hoist, a skip, a sectional counterweight therefor, guide means for said counterweight, said guide means engaging said counterweight along the lines of division between its sections, and means for raising the skip and lowering the counterweight, and vice versa.
60. In testimony whereof we hereby affix our signatures.

FRANK E. HULETT.
LEIF LEE.
